MODULATING MEANS FOR CATHODE RAY TUBES

Frederick Hermes Nicoll, Hounslow West, England, assignor to Electric & Musical Industries Limited, Hayes, England, a company of Great Britain

Application November 16, 1935, Serial No. 50,121
In Great Britain November 19, 1934

13 Claims. (Cl. 250—27)

The present invention relates to improvements in cathode ray tubes of the hard type.

A cathode ray tube is known which comprises a cathode, a modulating electrode or "modulator", one or more focusing electrodes, an anode and a fluorescent screen. Tubes of this kind are used for purposes such as television reception, received picture signals being applied between the cathode and modulator so as to vary the intensity of the ray reaching the screen and thus produce a corresponding variation in intensity of the fluorescent light emanating from this screen.

It has been found, however, that the modulation characteristic curves of such tubes, that is to say, the curves obtained by plotting modulator volts (relative to the cathode) as abscissae against fluorescent screen current as ordinates, are excessively curved, changes in fluorescent screen current for large changes in modulator volts being disproportionately large compared with the changes in fluorescent screen current produced by smaller changes in modulator volts.

It has also been found that the size of the spot varies with the modulator volts, generally increasing as the potential of the modulator approaches that of the cathode, thus giving rise to loss of detail in the reconstituted picture.

Furthermore, it has been found that it is not easy to secure a high sensitivity of control of the ray intensity over the useful working range. This sensitivity is measured by the negative voltage which has to be applied to the modulator to extinguish the ray, the sensitivity being highest when this voltage is least, provided that the current at zero modulator volts is unaltered.

Copending application No. 745,838, filed September 28th, 1934, describes an improved cathode ray tube of the hard type which, when associated with suitable electrical circuits, yields a characteristic curve of suitable shape and produces on the screen of the tube a spot whose size does not vary substantially with modulation potential. In that arrangement there are arranged within the envelope of the tube in the order stated, a cathode adapted to emit electrons, a first accelerating electrode, a decelerating and modulating electrode, a second accelerating electrode and a screen, the said accelerating and decelerating electrodes being so arranged that a ray constituted by said electrons can pass through them on to said screen, means for deflecting said ray over said screen, electrostatic or electromagnetic means for focusing said ray in a small spot upon said screen, means for applying to said accelerating electrodes potentials which are positive with

respect to the potential of said cathode, and means for maintaining said decelerating and modulating electrode at a potential not more positive than the potential of said cathode. In that arrangement electrons leaving the cathode were accelerated by the first accelerator electrode and thereafter slowed up as they entered a deceleration region in the neighbourhood of the decelerating and modulating electrode. The electrostatic field existing between the modulating electrode and the second accelerating electrode caused the electrons to be again accelerated towards the screen. The shape and disposition of the electrodes and the potentials applied to them were such that, an increase of potential of the modulator electrode, in the negative sense with respect to the cathode potential, so retarded an increased proportion of the electrons passing from the first accelerating electrode to the modulator electrode that they did not reach the accelerating field due to the second accelerating electrode and were reversed and flowed back to the first accelerating electrode.

With that arrangement however, the sensitivity of control of the ray intensity was not as high as is sometimes desired.

An object of the present invention is to provide an improved cathode ray tube which, when associated with suitable electrical circuits, will not only yield the advantages of the arrangement hereinbefore referred to, but will also provide a sensitivity of control of the ray intensity which is higher than with known tubes.

According to the present invention, in a cathode ray tube of the kind hereinbefore referred to, the decelerating and modulating electrode, which is disposed between the first and second accelerating electrodes, is provided with a diaphragm having an aperture, the effective thickness of the material surrounding this aperture substantially exceeding one-tenth of the diameter of the aperture. The diaphragm may be of relatively thick material, or of thin material shaped to form a flange surrounding the aperture whereby its effective thickness is increased. Alternatively the diaphragm may consist of a plurality of thin sheets spaced apart so as to form effectively the equivalent of a thick sheet.

There is less penetration of the anode field through the thick, or multiple, modulator diaphragm than through a thin diaphragm; hence the negative voltage which has to be applied to the modulator to extinguish the ray is less than with a thin modulator diaphragm. However, with many kinds of cathode ray tubes the in-

clusion of a thick modulator diaphragm would effect little or no increase in sensitivity because it would cause the intensity of the ray at zero modulator volts to fall also. Where, however, 5 a positive electrode is provided between the cathode and a modulator maintained at a potential not more positive than cathode potential, and the modulator is constructed in accordance with the present invention, the intensity of the ray at 10 zero modulator potential is not greatly influenced by the effective length of the aperture in the diaphragm, and the sensitivity of the tube is therefore increased.

Embodiments of the present invention will 15 now be described, by way of example, with reference to the accompanying diagrammatic drawing in which.

Fig. 1 illustrates a tube having a decelerator provided with a thick diaphragm.

20 Fig. 2 shows a circuit arrangement for supplying appropriate potentials to the various electrodes of a tube of the kind illustrated in Fig. 1.

Figs. 3 to 8 show alternative forms of decelerator electrode applicable to the tube shown in Fig. 1.

25 In the embodiment illustrated in Fig. 1, a cathode ray tube suitable for purposes of television reception, comprises an evacuated, sealed glass envelope consisting of a cylindrical portion 1 flaring out into a frusto-conical portion 2. The 30 diameter and length of the cylindrical portion 1 are about 1½ inches and 8 inches respectively the diameter of the base 3 of the frusto-conical portion 2 is about 9 inches, whilst the overall length of the envelope is about 19 inches.

35 Sealed internally to the closed end of the cylindrical portion 1 is a glass tubular portion 4 which projects internally from and lies wholly within the cylindrical portion 1. The tubular portion 4 is about ½ inch in internal diameter 40 and 6½ inches in length.

45 Disposed within the tubular portion 4 are a cathode heater 4A, a cathode 5, a cathode shield 6, a first accelerator 7, a decelerator 8 and a second accelerator 9, these electrodes being arranged within the glass tubular portion 4 in the order mentioned. The decelerator 8 is adapted to function as a modulator and the second accelerator 9 corresponds to what is sometimes known as the first anode of the tube. Leads to 50 the electrodes disposed within the glass tube 4 may be passed through a pinch 10 sealed into the closed end of the tubular portion 1, the leads to the cathode and its heater also serving as supports for these electrodes whilst the cathode 55 shield, the two accelerators and the decelerator are mounted as sliding fits within the glass tubular portion 4. Leads to the three last mentioned electrodes pass from the pinch 10 through holes such as 11, 12 in the side walls of the glass tube 60 4 and back through holes such as 13, 14 on to the electrodes. The second accelerator 9, about 3 inches in length, is mounted within the tubular portion 4 in such manner that 1 inch or more of the electrode protrudes beyond the tubular portion. If desired a lead may be taken to this protruding portion through the side wall of the cylindrical portion 1 of the envelope instead of from the pinch 10. All of the electrodes mentioned, except the heater, are of cylindrical shape 65 and are mounted co-axially within the envelope.

70 A second anode 15, in the form of a cylinder of 3½ inches length, is also mounted as a sliding fit within the cylindrical portion 1 of the envelope 75 in such manner that the second anode overlaps

the second accelerator or first anode by about ¼ of an inch.

On the inner side of the base 3 of the frusto-conical portion 2 of the envelope is deposited a fluorescent screen 16 of any known or suitable material. Either electrostatic or electromagnetic means such as two pairs of coils 17, 18 may be utilized to deflect the ray so as to scan the fluorescent screen 16 and these means may be situated, either inside or outside the tube between the 10 second anode 15 and the screen 16 and close to the second anode.

The cathode 5 may be of any suitable kind but preferably is in the form of a shallow open pill-box of ¼ inch diameter, electrons being emitted 15 from the flat circular base which is indirectly heated by means of the heater which lies within the box. The cathode may be coated with an electron emitting substance such as a mixture of strontium and barium oxides. 20

The shield 6 is also in the form of a pillbox, of about ½ inch length and diameter, having a central aperture 19 in its base and being disposed around the cathode 5 so that the cathode lies close to (but does not touch) the bottom of 25 the shield 6 and emits electrons through the aperture 19 in the base of the shield.

The first accelerator 7 is in the form of a very shallow open pill-box having a thin base; the box is about 2 millimetres in length and ½ inch diameter. It has a central aperture 20 in its base which is disposed about 3 millimetres away from the base of the shield 6 and the "skirt" of the first accelerator is turned toward the cathode 5. 30

The decelerator and modulator 8 is in the form 35 of a short cylinder, about ½ inch length and ½ inch diameter, with two thin discs 50 and 51 spaced 1 mm. apart and having apertures 50' and 51' disposed along its length somewhat nearer the first accelerator 7 than the second accelerator 9. 40 One end of the modulator 8 is about ¼ of an inch away from the first accelerator 7.

The second accelerator or first anode 9 bears 45 two thin discs, the one disposed at the end of the electrode lying closer to the modulator 8 having an aperture 22, and the other being disposed about 1 inch from the opposite end and having an aperture 23.

The second anode 15 carries no apertured discs, and a lead to this electrode may be taken through 50 the wall of the frusto-conical portion 2 of the envelope.

The apertures 19, 20, 50' and 22 are all 1.9 mm. in diameter, the aperture 51' in the disc 51 of the modulator 8 is 2.5 mm. in diameter, and the 55 aperture 23 in the second anode 15 is 3.8 mm. in diameter.

The various electrodes are maintained at their appropriate potentials by means of the circuit arrangement shown in Fig. 2. 60

An alternating potential difference, of any convenient voltage, is stepped up by means of a transformer 34 to 5,000 volts and rectified in the device indicated generally at 35. This steady potential is maintained across a potentiometer resistance 36, 37. 65

A tapping 38 on the potentiometer is connected both to the cathode 5 and to the cathode shield 6, these electrodes being in this manner maintained at about 30 volts positive with respect to 70 earth. Tappings 39, 40 and 41 on the potentiometer are connected to the first accelerator 7, the second accelerator 9 and the anode 15, respectively, in such manner that these electrodes are 75 respectively maintained at about 200 volts, 1,000 75

volts and 3,600 volts positive with respect to the earth potential.

Where the arrangement is to be used as a television receiver, the received signals are detected and amplified in a device shown generally at 42. The output from the device 42 is applied across a resistance 43 one end of which is earthed and the other end of which is connected to the modulator 8.

10 The modulator 8 derives a negative bias from the high tension supply to the tube, and the flow of picture signal current through resistance 43 is arranged to make the modulator 8 become more positive. The resultant bias is such that 15 the picture signals operate to vary the potential of the modulator 8, relative to the cathode, from zero down to about -12 volts, at which voltage the ray is extinguished.

15 It is believed that the operation of the tube 20 is somewhat as follows:—

Referring more particularly to Fig. 1, electrons emanate from the cathode 5 with random velocities and directions. The electrostatic accelerating field existing between the positive first 25 accelerator 7 on the one hand and the earthed cathode 5 and shield 6 on the other hand has the effect of extracting a large number of electrons from the cathode and concentrating these electrons so as to pass through the aperture 21 30 in the modulator 8.

The modulator is at a negative potential with respect to the first accelerator 7 so that between these two electrodes the electrons are decelerated and a deceleration region is formed close to the 35 apertures 50' and 51' in the decelerator 8.

The second accelerator 9 is at a high positive potential with respect to the decelerator 8 and the accelerating field which exists between these two electrodes extends into the deceleration region of the tube. The velocities (in the direction 40 of the axis of the tube) with which the electrons emerge from the cathode 5 are small compared to the axial velocities which they subsequently acquire owing to the electrostatic accelerating field existing between the various electrodes, and electrons which emerge from the cathode with comparatively large transverse velocities (say not less than 0.2 volt) are to a very large extent filtered out by the modulator 8 so that the electrons drawn from the deceleration region toward 45 the second accelerator 9 have almost the same axial and radial velocities and hence can be brought to a very sharp focus on the fluorescent screen 16. The focusing is effected in the following manner.

Between the deceleration region and the distant end of the second accelerator or first anode 9 the electrons tend to diverge owing to the shape of the electrostatic fields produced between the 50 electrodes. On reaching the comparatively strong electrostatic field maintained between the adjacent ends of the first and second anodes, however, the diverging electrons are concentrated or focused back on to the axis of the tube and at 55 the same time accelerated towards and through the second anode 15. The field between these two electrodes acts upon the diverging cone of electrons in much the same way as a lens acts upon a diverging beam of light, and for this reason the arrangement of first and second anodes 60 may be called an "electron lens". In the present case the cone of electrons which is diverging on entering the electron lens emerges as a converging cone and is brought to a focus upon the fluorescent screen 16.

It has been found that with this arrangement a spot of very small size can be obtained upon the screen and that changes in size of the spot, with changes in modulator volts, are less than the corresponding changes which have been observed in tubes of known kind.

It is found that, if the potential on the modulator 8 is increased negatively with respect to the cathode, the current flowing to the first accelerator increases, and on plotting first accelerator current as ordinates and modulator volts as abscissae a roughly straight line of negative slope is obtained over the working range (0 to -12) of modulator volts.

The tube shown in Fig. 1 is similar to that shown in Fig. 1 of the co-pending application Serial No. 745,838, above referred to, with the exception that in the example shown in the earlier application the decelerating and modulating electrode 8 has a single thin disc having an aperture 1.9 mm. in diameter. With that tube, the negative voltage required to extinguish the ray is 30 volts, whereas, when the modulator is provided with a second apertured disc, as shown in Fig. 1 of the present specification, the voltage required to extinguish the ray is reduced to 12. The thickness of the material in which the aperture is formed is in this way effectively increased to 1 mm. although the actual material of the diaphragm may be thin.

With the particular arrangement of diaphragms described, the shape of the modulator characteristic is not appreciably changed from that with the single diaphragm although its steepness is increased. The focusing is also substantially unaffected. By modifying the sizes of the apertures and their separation, however, certain changes in the shape of the characteristic can be effected.

The apertures in the diaphragms may if desired be made of equal diameter, or the larger diameter aperture in the arrangement first described may be arranged, for some purposes, further from the cathode than the aperture of smaller diameter.

A similar effect to that above described can be obtained with a single diaphragm of thin material by increasing the thickness of the material of the diaphragm immediately surrounding the aperture. Fig. 3 shows an example of a modulator electrode 8a, applicable to the tube shown in Fig. 1, in which the diaphragm 52 is provided with a flange or lip 53 around the aperture 52'. The lipped portion may be of cylindrical shape, as shown, giving an effect nearly equivalent to that of two apertures of equal diameter, or it may be conical, as shown at 54 in the modulator 8b shown in Fig. 4, or of other flared shape, giving the effect of apertures of different diameter. The behaviour of lipped apertures resembles closely that of apertures in equivalently spaced diaphragms provided that the distance between such diaphragms (and therefore the axial length of the lipped portion in the diaphragm with a lipped aperture) is not unduly great. The distance between the diaphragms is usually less than the diameter of either of the apertures. The lips may project either towards or away from the cathode and they may flare in either direction.

A further arrangement, which is nearly equivalent to that using multiple diaphragms, involves the use of relatively thick material for the diaphragm, as 55 (Fig. 5).

In Fig. 6, a single diaphragm 56, 1.0 mm. thick,

having an aperture 56' tapering from 1.9 mm. at one face to 2.5 mm. at the other face, is approximately equivalent in its behaviour to the two thin diaphragms shown in Fig. 1. The aperture may also be made of other shapes.

Three or more diaphragms may be used and the apertures therein may be equal to or different from one another according to circumstances. In the example shown in Fig. 7, three diaphragms 10 57, 58 and 59 are used and the aperture 58' in the middle diaphragm 58 is made smaller than the apertures 57' and 59' in the two outer diaphragms. The equivalent aperture can also be made in a single diaphragm of thicker material, 15 the aperture having three portions of cylindrical shape (of different diameters corresponding to the apertures in the three separate diaphragms) united by flaring portions. Alternatively the boundaries of the aperture in the thicker material may be curved as shown in Fig. 8, for example the cross section of the boundaries in planes containing the axis may be part-circular.

When the modulator diaphragm has the form shown in Fig. 8 or the approximately equivalent 25 form which can be made with three diaphragms having the apertures in the outer diaphragms larger than that in the middle diaphragm, the size of the aperture at the middle is preferably selected as small as possible consistent with no 30 decrease in the current in the tube at zero modulator voltage due to the return of electrons from the modulator, and the diameters of the aperture at the faces of the diaphragm are arranged to give maximum sensitivity and current through 35 the tube.

I claim:

1. Cathode ray tube apparatus comprising a cathode ray tube of the hard type having an envelope, and arranged therein, in the order 40 stated, a cathode adapted to emit electrons, a first accelerating electrode, a decelerating and modulating electrode, a second accelerating electrode, and a screen, the said accelerating and modulating electrodes being so arranged that a 45 ray constituted by said electrons can pass through them on to said screen, means for deflecting said ray over said screen, force field means for focusing said ray in a small spot upon said screen and means for applying to said accelerating electrodes 50 potentials which are positive with respect to the potential of said cathode, and means for maintaining said decelerating and modulating electrode at a potential not more positive than the potential of said cathode, characterized in that 55 said decelerating and modulating electrode is provided with a diaphragm having an aperture, the effective thickness of the material surrounding said aperture substantially exceeding one-tenth of the diameter of said aperture.

60 2. Cathode ray tube apparatus as claimed in claim 1, wherein said diaphragm in the decelerating and modulating electrode has a thickness substantially exceeding one-tenth of the diameter of said aperture.

65 3. Cathode ray tube apparatus as claimed in claim 1, wherein said diaphragm in the decelerating and modulating electrode is provided with a flange surrounding the aperture therein.

4. Cathode ray tube apparatus as claimed in 70 claim 1, wherein the cross section of the aperture in the diaphragm of the decelerating and modulating electrode is different at different points along the axis of the tube.

5. Cathode ray tube apparatus as claimed in 75 claim 1, wherein the cross section of the aperture

in the diaphragm of the decelerating and modulating electrode is larger at the end of said aperture nearer said cathode than at the end of said aperture nearer said screen.

6. Cathode ray tube apparatus as claimed in 5 claim 1, wherein the cross section of the aperture in the diaphragm of the decelerating and modulating electrode is larger at the end of said aperture nearer said cathode than at a point midway between the ends thereof.

7. Cathode ray tube apparatus as claimed in 10 claim 1, wherein the diaphragm of said decelerating and modulating electrode comprises a plurality of apertured plates located one behind another along the electron path.

8. Cathode ray tube apparatus as claimed in 15 claim 1, wherein the diaphragm of said decelerating and modulating electrode comprises a plurality of thin apertured plates located one behind another along the electron path, the distance between the first and last of said plates being substantially more than one-tenth of, but not more than, the diameter of the smallest of the apertures in said plates.

9. Cathode ray tube apparatus as claimed in 25 claim 1, wherein the diaphragm of said decelerating and modulating electrode comprises a plurality of apertured plates located one behind another along the electron path, the apertures in at least two of said plates being of different diameters.

10. Cathode ray tube apparatus as claimed in 30 claim 1, wherein the diaphragm of said decelerating and modulating electrode comprises at least three apertured plates, the apertures in the outer two of said three plates being of larger diameter 35 than the aperture in the inner of said three plates.

11. Electronic apparatus including a cathode ray tube of the hard type comprising an envelope, and disposed within said envelope, in the order 40 named, a cathode, an accelerating electrode having an apertured diaphragm, a modulating electrode having an apertured diaphragm the effective thickness of the material surrounding the aperture therein substantially exceeding one-tenth of the diameter of said aperture, but not exceeding the diameter of said aperture, a second 45 accelerating electrode having at least one apertured diaphragm, an anode co-operating with said second accelerator to form an electron lens, a screen and means to apply potentials to the electrodes.

12. Cathode ray tube apparatus comprising a cathode ray tube of the hard type having a cathode, a first accelerating electrode, a modulator, and a second accelerating electrode, said 55 modulator being in the form of a cylinder of substantially the same diameter as said accelerators, disposed between said accelerators and provided with a diaphragm placed intermediate its ends and having an aperture, the effective thickness of 60 the material surrounding said aperture substantially exceeding one-tenth of the minimum diameter of said aperture, means for maintaining said modulating electrode at a potential not exceeding the potential of said cathode, means for 65 maintaining said first accelerating electrode at a positive potential relative to said cathode, and means for maintaining said second accelerating electrode at a potential substantially more positive than that of said first accelerating electrode. 70

13. Cathode ray tube apparatus comprising a cathode ray tube of the hard type having an envelope, and arranged therein in the order stated 75 a cathode adapted to emit electrons, a first accelerator adapted to project a beam of said elec-

trons away from said cathode, a modulator having an apertured diaphragm and serving to retard said beam so that a proportion of said electrons, varying with the potential of said modulator, is reversed and caused to flow to said first accelerator, a second accelerator serving to accelerate away from said cathode the remainder of said electrons, means for focusing the beam constituted by said remainder, and a screen adapted 5 to receive the focused beam, means for maintaining said first accelerator positive with respect to said cathode, means for maintaining said second accelerator positive with respect to said first accelerator, and means for maintaining said modulator at a potential not more positive than the potential of said cathode and for applying modulating potential differences between said modulator and said cathode, the effective length of the aperture in said diaphragm being more than one-fifth of its minimum diameter but not more than its minimum diameter, whereby the penetration through said aperture of the accelerating field due to said second accelerator is brought to a minimum consistent with the maintenance of a 10 sufficient focused electron beam when the modulator potential equals the cathode potential.

FREDERICK HERMES NICOLL.
